GASOLINE DISPENSING PUMP

Roger Kennedy, Studio City, and Peter B. Rothschild,
Santa Fe Springs, Calif., assignors to Pan-Nova, Inc.,
Santa Fe Springs, Calif.

Filed Jan. 10, 1972, Ser. No. 216,886

Term of patent 14 years

Int. Cl. D23—01
U.S. Cl. D52—2 A

FIG. 5.

FIG. 6.

FIG. 7.

FIG. 1 is a front perspective view of a Gasoline Dispensing Pump showing our new design, the rear being a mirror image thereof;

FIG. 2 is a left side elevational view thereof;

FIG. 3 is a right side elevational view thereof;

FIG. 4 is a top plan view thereof;

FIG. 5 is a front perspective view of another embodiment of our new design, the rear being identical, wherein dual hose outlets are provided thereon;

FIG. 6 is a side elevational view of FIG. 5 as taken from arrows 6;

FIG. 7 is a top plan view of FIG. 5 as taken from arrow 7.

We claim:

The ornamental design for a gasoline dispensing pump, substantially as shown and described.
